UNITED STATES PATENT OFFICE.

FRANK L. MILLER, JR., OF CHATTANOOGA, TENNESSEE.

DESIGN FOR A DOLL.

59,666.

Specification for Design.

Patented Nov. 15, 1921.

Application filed September 24, 1921. Serial No. 503,116. Term of patent 14 years.

To all whom it may concern:

Be it known that I, FRANK L. MILLER, Jr., a citizen of the United States, residing at Chattanooga, in the county of Hamilton and State of Tennessee, have invented a new, original, and ornamental Design for Dolls, of which the following is a specification, reference being had to the accompanying drawing, forming part hereof.

The figure is a plan view of a doll, showing my new design.

I claim:

The ornamental design for a doll as shown.

FRANK L. MILLER, JR.
